UNITED STATES PATENT OFFICE

2,089,550

PRINTING PLATE BASE

Horace W. Hacker, La Grange, Ill.

Application May 6, 1935, Serial No. 20,069
Renewed June 1, 1937

5 Claims. (Cl. 101—382)

My invention relates to lumber from which printing plate bases are to be cut and generally speaking has for its purpose an elementary construction of lumber whereby printing plate bases 5 cut therefrom will possess a high degree of stability as to size and form under atmospheric and moisture conditions incident to their use and wherein elements enhancing such stability also serve as reinforcements against side lock-up pressure. Furthermore, my present invention is designed to facilitate the planing for height of printing plate bases cut from lumber characterized by wood blocks secured between metal plates and to simplify and cheapen the manufacture of such lumber as is disclosed in Figure 2 of my copending application Serial Number 759,571; filed December 28, 1934, and now Patent No. 2,083,705.

In the drawing chosen to illustrate my invention 20 the scope whereof is set forth in the appended claims

Figure 1 is a fragmentary perspective view of a printing plate base cut from lumber constructed in accordance with my invention;

Figure 2, a section on the line 2—2 of Figure 25 1;

Figure 3, a view similar to Figure 1 showing an alternative form of my invention;

Figure 4, a section on the line 4—4 of Figure 30 3; and

Figure 5, a fragmental perspective showing of a modification showing the veneer facings of the lumber kerfed in cross directions.

In Figures 1 and 2 my improved lumber is 35 shown as comprising a plurality of wood blocks 10 positioned between thin metal plates 11 and 12. The blocks 10 are arranged with their adjacent faces slightly spaced apart to eliminate detrimental and undesirable cumulative effect of side 40 swelling of the blocks which otherwise might arise were the blocks arranged with their side faces in contact. The metal plates 11 and 12 are shown as having holes punched therein to provide formations 13 projecting from their inner faces and 45 which formations are engaged in the adjacent faces of the blocks 10, thus forming an interfit between the blocks and plates which assists materially in preventing any relative lateral displacement of the blocks and plates, while the latter also serve as reinforcements against side lock-up pressure in bases cut from the finished lumber. It will of course be understood that the blocks 10 and plates 11 and 12 are suitably cemented together. In order to provide for easy 55 planing of bases cut from my lumber I cement to

the outer face of each of the plates 11 and 12 strips of wood veneer 14 having their adjacent edges spaced apart to avoid cumulative effects of swelling. Preferably, but not necessarily, I arrange the strips 14 at an angle to both axes of the 5 lumber which eliminates the necessity of carefully positioning plates upon a cut base in order to miss the space between the veneer strips at the points where the plate is nailed to the base.

The construction shown in Figures 3 and 4 differs from that shown in Figures 1 and 2 in that each succeeding hole is punched in the metal plates in a direction opposite to the preceding one to provide projections 15 and 16 on respective faces of each plate, the projections 15 being engaged in the blocks 10 and the projections 16 being engaged in the veneer strips 14, whereby the plates have interconnection with both the blocks 10 and the veneer strips 14.

In order to facilitate the application of the 20 veneer strips 14 at an angle to both axes of the lumber I apply continuous sheets of wood veneer to the outer face of each metal plate 12 and 11 and then kerf each sheet of veneer on lines parallel to each other and at an angle to both axes 25 of the lumber. This is a desirable manner of positioning the strips 14 but my invention is not limited thereto as the fundamental purpose of the kerfing is to separate the sections of veneer and any manner of kerfing will accomplish the 30 end.

In Figure 5 I show the veneer facings of the 35 lumber kerfed in cross directions whereby the veneer sheets are cut up into spaced apart small units 17. This construction further enhances the 40 anti-warping characteristics of the veneer facings.

I claim:

1. Lumber from which printing plate bases are 45 to be cut and the contacting surfaces of whose elements are cemented together, comprising metallic sheets, a plurality of wood blocks between the sheets, and a plurality of wood veneer sections secured to and overlying the outer face of each metallic sheet, the adjacent edges of said veneer sections being disposed in spaced relation.

2. Lumber from which printing plate bases are 50 to be cut and the contacting surfaces of whose elements are cemented together, comprising metallic sheets having formations on their opposed faces, a plurality of wood blocks between the sheets into which said formations are engaged, and a plurality of wood veneer sections secured to and overlying the outer face of each metallic 55

sheet, the adjacent edges of said veneer sections being disposed in spaced relation.

3. Lumber from which printing plate bases are to be cut and the contacting surfaces of whose elements are cemented together, comprising metallic sheets having openings punched therein to provide formations on their opposed faces, a plurality of wood blocks between the sheets into which said formations are engaged, and a plurality of wood veneer sections secured to and overlying the outer face of each metallic sheet, the adjacent edges of said veneer sections being disposed in spaced relation.

4. Lumber from which printing plate bases
15 are to be cut and the contacting surfaces of whose
elements are cemented together, comprising me-
tallic sheets each having formations projecting
from both faces, a plurality of wood blocks be-
tween the sheets into which the formations on
20 opposed faces of the sheets are engaged, and a
plurality of wood veneer sections secured to and

overlying the outer face of each metallic sheet and into which formations projecting from the outer face of the related sheet are engaged, the adjacent edges of said veneer sections being disposed in spaced relation.

5. Lumber from which printing plate bases are to be cut and the contacting surfaces of whose elements are cemented together, comprising metallic sheets each having openings punched therein to provide formations projecting from each face thereof, a plurality of wood blocks between the sheets into which the formations on opposed faces of the sheets are engaged, and a plurality of wood veneer sections secured to and overlying the outer face of each metallic sheet and into which formations projecting from the outer face of the related sheet are engaged, the adjacent edges of veneer sections being disposed in spaced relation. 10 15

HORACE W. HACKER. 20
